F. JANTSCH.

BREECH CLOSURE FOR MORTARS AND THE LIKE.

APPLICATION FILED JULY 28, 1915.

ATTY.

UNITED STATES PATENT OFFICE.

FRANZ JANTSCH, OF GABLONZ, AUSTRIA-HUNGARY.

BREECH-CLOSURE FOR MORTARS AND THE LIKE.

1,161,686.

Specification of Letters Patent. Patented Nov. 23, 1915.

Application filed July 28, 1915. Serial No. 42,307.

To all whom it may concern:

Be it known that I, FRANZ JANTSCH, a citizen of the Empire of Austria-Hungary, residing at 14 Brandlgasse, Gablonz a. N., in the Kingdom of Bohemia and Empire of Austria-Hungary, have invented new and useful Improvements in Breech-Closures for Mortars and the like, of which the following is a specification.

10 My invention relates to an improved breech-closure for mortars or cannons of the kind used for firing salutes, joy-shots, signaling purposes and the like.

According to this invention the breech-plug is provided with a device capable of holding the cartridge which is to be introduced into the gun or tube of the mortar or the like, and the striking-pin movable within the breech-plug is retained in its position of rest, as long as the breech-plug is not inserted into the mortar or the like and is not locked in its working position. In this way, the danger of an undue igniting of the cartridge taking place out of the mortar or the like and without the breech-plug being locked in the interior of the mortar and the like is avoided, even when the breech-closure together with the cartridge is dropped by inadvertence.

30 In the accompanying drawing forming a part of this specification and in which similar letters of reference relate to corresponding parts throughout the several views, Figure 1 is an elevation, partly in longitudinal section, of a form of execution of my improved arrangement. Figs. 2 and 3 are cross-sections on line A—B of Fig. 1, said cross-sections showing the movable parts of the device in two different positions. Fig. 40 4 is a front view toward the inner end of the breech-closure.

Referring now to the drawings the cylindrical breech-plug *a* is provided with two handles *b* and on its periphery with a projection or nose *c* which engages into a corresponding recess or notch *d* at the extremity of the gun or tube of the mortar and the like so as to keep the breech-plug in its proper position. Within the breech-plug the striking-pin or percussion-bolt *f* is axially movable against the action of a spring or coil *g*. Said striking-pin is secured in its position of rest (Figs. 1 and 2) by a resilient bolt *h* which is provided with an aperture *i* for passage of the larger part of the striking-pin *f*, said aperture *i* having

a small downwardly directed extension *c'* adapted to receive only the part of the striking-pin of less diameter. By the action of a spring or coil *k* the bolt *h* is forced into its locking position, in which the projecting larger part of the striking-pin rests against said bolt *h*. In the locking position (Figs. 1 and 2) the upper extremity of the bolt *h* penetrates into a lateral recess *l* of the breech-plug *a*. In this recess *l* is engaged a bolt *m* transversely movable in the gun or tube of the mortar and the like. Said bolt *m* can be shifted to and fro by means of a handle *n* adapted to act upon an eccentric *p* keyed upon a shaft *o* supported by the extremity of the gun or tube of the mortar and the like. To this purpose the eccentric *p* engages in a cam-shaped recess *q* of the bolt *m*.

75 The extremity of the breech-plug serving as an abutment for the cartridge *r* is provided with an upwardly directed lateral recess *s* for receiving the back *r'* of the cartridge. To this effect the edge of the cartridge is shoved transversely into said recess *s*.

80 The manipulation and mode of operation of the breech-closure forming the object of my invention are the following: The breech-plug *a*, after the striking-pin or percussion bolt *h* being secured in its position of rest and the cartridge *r* having been inserted into the lateral recess *s*, is introduced into the posterior extremity of the gun or tube 85 of the mortar and the like, so that the projection or nose *c* registers with the recess *d*. Subsequently, the bolt *m* intended for locking the breech-plug in its position of work (Fig. 3) is moved by means of the handle *n*, 90 so that said bolt *m* drives back the resilient bolt *h*. In consequence thereof the larger aperture *i* of the bolt *h* registers with the part of the striking-pin *f* of larger diameter, so that the striking-pin can freely move in a 100 forward direction. Now, the cartridge can be ignited by percussion upon the striking-pin, whereby the mortar or the like is fired.

What I claim and desire to secure by Letters Patent of the United States is:— 105

1. In a firearm, in combination, a breech-plug, a striking-pin mounted within the breech-plug, resilient means for maintaining the striking-pin normally in retracted, inoperative position, a locking member for 110 the striking-pin adapted normally to obstruct the latter to prevent its movement

into operative, firing position, and a locking member for the breech-plug adapted upon arrival of the latter at its operative position to lock it in the firearm breech and to move the locking member for the striking-pin automatically into inoperative, unobstructing position.

2. In a firearm, in combination, a breech-plug having a recess, a striking-pin mounted within the breech-plug and being provided with a shoulder, resilient means for maintaining the striking-pin normally in retracted, inoperative position, a locking member for the striking-pin mounted within the breech plug recess, resilient means for normally maintaining the said locking member in operative position in engagement with the shoulder of the striking-pin to lock the latter, and a locking member for the breech-plug mounted within the firearm breech and adapted to be engaged within the breech-plug recess when the said plug arrives at its operative position, the last-named locking member being adapted to engage the locking member for the striking-pin to move the same into inoperative position.

3. In a firearm, in combination, a breech-plug having a recess, a striking-pin mounted

within the breech-plug and provided with a shoulder, resilient means for maintaining the striking-pin normally in retracted, inoperative position, a locking member for the striking-pin mounted within the breech-plug recess, resilient means for normally maintaining the said locking member in operative position in engagement with the shoulder of the striking-pin to lock the latter, a locking member for the breech-plug mounted within the firearm breech and adapted to be engaged within the breech-plug recess when the said plug arrives at its operative position, the last-named locking member being adapted to engage the locking member for the striking-pin to move the same into inoperative position, and means provided exteriorly upon the firearm by which the locking member for the breech-plug may be operated.

In testimony whereof I have signed my name to this specification in the presence of two subscribing witnesses.

FRANZ JANTSCH.
